DEFLECTING TOOLS

Onos M. Lindsay, Long Beach, Calif., and William G. James, Denver, Colo., assignors to Eastman Oil Well Survey Company, Denver, Colo., a corporation of Delaware

Application December 24, 1954, Serial No. 477,437

13 Claims. (Cl. 255—1.6)

This invention relates to new and useful improvements in deflecting tools.

One object of the invention is to provide an improved deflecting tool for effectively drilling a well bore at an angle from the vertical whereby directional drilling of the well may be accomplished.

An important object of the invention is to provide an improved deflecting tool adapted to be connected in the lower portion of a drill pipe or string and having a radially extensible means for urging the lower portion of the drill pipe and the drill bit attached thereto laterally toward one side of the well bore, whereby subsequent rotation of the drill pipe and bit will result in drilling the well bore at an angle with respect to the remainder of said bore.

Another object is to provide a deflecting tool having an improved deflecting element which is normally in a retracted position and is adapted to be positively and mechanically moved radially outwardly by the imposition of the weight of the drill pipe thereon, whereby said element is automatically moved into expanded or extended position when the drill pipe weight is imposed upon the bit to perform the drilling operation.

Another object is to provide an improved deflecting tool having telescoping sections which are adapted to mechanically urge a deflecting element outwardly into a radially extended position and to positively maintain the element in such position when the sections are telescoped relative to each other; retraction of the deflecting element being automatically accomplished when the members are moved to an extended position.

A particular object is to provide a deflecting tool having a metallic deflecting element which is adapted to be moved outwardly by an expander which positively maintains the element in expanded position; said tool being arranged to be mounted in close proximity to or adjacent the drill bit whereby when the deflecting element is expanded, a constant radial pressure or lateral force is maintained upon the bit to constantly force said bit laterally of the well bore and thereby accomplish a directional drilling operation.

Still another object is to provide an improved deflecting tool, of the character described, which is simple in construction and which comprises a unitary assembly capable of being readily connected in the usual drill pipe; said tool, having its deflecting element mounted so that the element may remain stationary and will merely slide down the wall of the bore when the drill pipe and bit are rotated to perform the drilling operation.

A further object is to provide a tool, of the character described, including an improved orienting means whereby the deflecting element may be accurately oriented to properly position the deflecting element of the tool in a desired azimuthal position.

Another object is to provide a deflecting tool, of the character described, wherein the main portion of the tool comprises a pair of telescoping sections, the relative

2

movement of which with respect to each other, control the expansion or radial extension or the retraction of the deflecting element; the deflecting element coacting with a tapered expander which may be rotatable with the telescoping sections or which may be so mounted that said expander remains stationary while said sections rotate.

The construction designed to carry out the invention will be hereinafter described, together with other features thereof.

The invention will be more readily understood from a reading of the following specification and by reference to the accompanying drawings forming a part thereof, wherein an example of the invention is shown, and wherein:

Figure 1 is an elevation of the lower portion of a drill pipe within a well bore and showing the improved deflected tool connected therein,

Figure 2 is a vertical sectional view of a deflecting tool, constructed in accordance with the invention, and illustrating the deflecting element thereof in its expanded position,

Figure 3 is a similar view, with the deflecting element in retracted position,

Figure 4 is a horizontal, cross-sectional view, taken on the line 4—4 of Figure 2,

Figure 5 is a horizontal, cross-sectional view, taken on the line 5—5 of Figure 3,

Figure 6 is a horizontal, cross-sectional view, taken on the line 6—6 of Figure 3,

Figure 7 is a longitudinal, sectional view of a modified form of the invention, showing the deflecting element in expanded position,

Figure 8 is a similar view with the deflecting element retracted,

Figure 9 is a horizontal, cross-sectional view, taken on the line 9—9 of Figure 7,

Figure 10 is a view, partly in section and partly in elevation of still another form of the invention, and

Figure 11 is a horizontal, cross-sectional view, taken on the line 11—11 of Figure 10.

In the drawings the numeral 10 designates the usual drill pipe or drill stem which is adapted to extend through a well bore W and which is utilized to impart rotation to the drill bit 11 connected to the lower end of said drill pipe. The improved deflecting tool A comprising the present invention is arranged to be interposed between the drill pipe 10 and the drill bit 11 and said tool includes a deflecting element which is generally indicated at B and which is movable radially of the body between a retracted and an expanded or extended position. When in an expanded position as illustrated in Figure 1, portions of the deflecting element engage the wall of the well bore W at one side of the bore just above and in close proximity to the drill bit 11 and said element functions to urge the lower portion of the drill pipe 10 in a direction away from the point of contact of the element with the wall of the bore. It is apparent that with the deflecting element in its expanded or radially extended position, the bit 11 is constantly urged toward that area of the wall of the well bore which is directly opposite the deflecting element and the subsequent rotation of the drill pipe and bit results in a drilling of the well bore at an angle with respect to the main portion of said bore.

The deflecting tool A is clearly shown in Figures 2—6 and includes a pair of telescoping sections T and T1. The upper section T includes an elongate tubular body 12 having an axial bore 13 extending entirely therethrough, and the drill pipe 10 is adapted to have its lower end secured to the upper end of said body. An external

flange 12a is formed on the upper portion of the body and, the underside of said flange forms an annular shoulder 14. Nearer its lower end, the tubular body 12 is provided with outwardly extending drive lugs or blocks 15.

The lower telescoping section T1 is formed of a generally cylindrical sleeve 16 which engages over the lower portion of the tubular body 12 of the upper section. The sleeve is provided with diametrically opposed slots 17, which slots receive the outwardly directed drive lugs or blocks 15 on the body 12, whereby the upper section T is rotatively coupled to the lower section while permitting telescoping movement of the sections with respect to each other. The lower end of the section T1 is formed with an expander 18 which is circular in cross-section and which is gradually enlarged in diameter toward its lower end, whereby its outer surface 18a is inclined downwardly and outwardly. The drill bit 11 is threaded into the lower end of the lower section T1, as clearly shown in Figure 2. The deflecting element B comprises a generally arcuate wedge 19 which has its upper end pivoted at 20 to the lower end of an outer sleeve 21. As shown in Figure 6, the wedge 19 is disposed at one side of the tool and extends only through a relatively small portion of the circumference of the tool. The outer sleeve 21 surrounds the upper portion of the sleeve 16 of the main section T1 and the lower portion of the upper section T and is rotatably suspended from the upper surface 12b of the external flange 12a on the body of said upper section. The outer sleeve 21 is retained against displacement from its supporting surface 12b by a retaining collar 22.

The telescoping sections T and T1 are normally urged toward an extended position as illustrated in Figure 3 by a coil spring 23 which is confined between the shoulder 14 on the upper section T and the upper end 16a of the sleeve 16 of the lower section T1. When the sections are extended with respect to each other, the arcuate deflecting element B is in a retracted position, since its lower end is in a plane above the inclined surface 18a of the expander 18. At certain times it is desirable to prevent rotation of the outer sleeve 21 which carries the deflecting element B with respect to the sections and for this purpose the lower section T1 has a pair of diametrically opposed recesses or grooves 24 (Figures 3 and 4) formed in its external surface. As shown in Figure 3, each recess is open at its lower end and terminates at an external shoulder 24a formed on the body 16 of said lower section. A pair of pins 25 are secured within the wall of the outer sleeve 21 and are located diametrically opposite each other, each pin 25 projects inwardly into the bore of the sleeve 21 and is adapted to engage within one of the recesses 24 when the sections are extended. At such time, the sleeve is locked against rotation with respect to the lower section T1, and since the lower section is rotatively coupled to the upper section at all times, the deflecting element B is locked against rotation with respect to the drill pipe. When the sections are moved into a telescoped position, as illustrated in Figure 2, each pin 25 moves out of its recess 24 to the dotted line position 25a in Figure 3, whereby the sections may be rotated, while the wedge element B and its carrying sleeve 21 may remain stationary. Although a pair of pins 25 and recesses 24 are illustrated, it is evident that only one such pin and recess would suffice. To facilitate rotation of the upper section with respect to the outer sleeve, a suitable bearing surface 27 may be provided between the upper end of the sleeve and the retaining collar 22.

It is apparent that when the pin 25 is engaged within its recess 24, the deflecting element is locked in a fixed position with respect to the drill pipe. By locating a magnet 28 (Figure 1) in the drill pipe in a known radial position or relationship to the deflecting element, it is possible to determine the radial position or azimuth of the deflecting element by known methods of bottom-

hole orientation. For example, a method of orientation which may be employed is that shown in the patent to Miller, 2,327,658, or Hyer, 2,120,670. With the magnet 28 in a known radial relationship to the deflecting element when the latter is locked against rotation on the drill pipe, a suitable well survey instrument illustrated in dotted lines in Figure 1, may be lowered within the pipe to an elevation substantially opposite the magnet; thereafter the instrument is operated to record the azimuthal position of the magnet and by subsequent examination of the records so made, the compass position of the deflecting element may be readily determined after the tool has been lowered into position within the well bore.

15 In the operation of the tool, the parts are normally in the position shown in Figure 3 with the sections T and T1 in an extended position. In such position, the deflecting element is in its retracted position and each orienting pin 25 is engaged in its recess 24. As explained, the drill 20 pipe is connected to the upper section T which is coupled to the lower telescoping section T1 through the drive lugs 15 and slots 17.

When the tool reaches bottom, the compass position of the deflecting element B may be determined by ascertaining the position of the magnet 28 by means of any well-known orientation method. Thereafter, the drill pipe may be rotated to locate the deflecting element in the desired azimuthal position.

Upon being lowered to bottom, the drill bit strikes the 30 bottom of the well bore and thereafter the weight of the drill pipe is imposed upon the tool. This causes a further telescoping of the upper section T with respect to the lower section T1, such movement being permitted by the coil spring 23. The downward movement of the upper section T with respect to the lower section T1 moves the arcuate deflecting element B downwardly along the inclined face 18a of the expander 18 to cause the deflecting element to be moved radially outwardly into contact with the wall of the well bore W. At the same time, the 35 downward movement of the upper section with respect to the lower section results in disengaging the pins 25 from the recesses 24 because the outer sleeve 21 moves downwardly with the upper section. The connection between the outer sleeve 21 and the lower section T1, as effected 40 by the pins 25 and recesses 24, is released and thereafter the sections T and T1 may be rotated with respect to said outer sleeve.

When the deflecting element B is moved radially outwardly, said element contacts the wall of the bore and 45 applies a lateral pressure to the drill bit 11 to urge the bit in a direction which is opposite the position of the deflecting element, and therefore the bit is urged toward one side of the bore. By proper orientation of the element, the drill bit is urged laterally in a desired compass direction so that subsequent rotation of the drill pipe and of the bit will perform the drilling operation. So long as the weight of the pipe is imposed upon the tool, the sections T and T1 remain in fully telescoped position and maintain the deflecting element in its radially expanded 50 position. Obviously, the element remains stationary during rotation of the drill pipe and drill bit, and as drilling proceeds, the deflecting element merely slides down the wall of the well bore but constantly maintains a lateral pressure on the bit to urge it toward the opposite wall. 55 It is preferable that the element B be located in close proximity or adjacent to the drill bit 11 so that the required constant lateral pressure can be maintained throughout the drilling operation.

In Figures 7 and 8, a modified form of the invention 70 is shown. In this form, the tool A1 is constructed of an upper telescoping section T3 and a lower telescoping section T4. The upper section comprises a sub or coupling member 30 which has connection with the drill pipe 10. The sub 30 is tubular, being formed with a bore 31, and a sleeve 32 is connected to and depends from said sub.

The lower end of the sub is formed with downwardly extending clutch teeth 33.

The lower telescoping member T4 includes a tubular body 34, having an axial bore 35. A wash tube or conductor 36 is threaded into the upper end of the bore and extends upwardly through the bore 31 of the sub 30; a suitable packing 37 seals off around the tube and said tube functions as a conductor for establishing communication between the bore 10a of the drill pipe and the bore 35 of the body 34. The upper end of the body 34 is formed with clutch teeth 38 which are adapted to interengage the teeth 33 of the sub 30 when the sections T3 and T4 are in fully telescoped position. The clutch teeth 33 and 38 are of considerable strength and function to carry the load when rotation is imparted from the section T3 to the section T4 during the drilling operation. A coil spring 39 which is disposed between the sub 30 and the body 34 exerts its pressure to constantly urge the sections toward an extended position.

The lower end of the body 34 of the lower section T4 is formed with an expander 40 having an inclined expanding surface 40a and the drill bit 11 is connected to the lower end of the body 34. The body 34 is rotatively connected to the sub 30 by splines 41 formed on the body which coact with splines 42 provided within the bore of the sleeve 32; as explained, the sleeve 32 is connected with and depends from the sub 30 of the upper section T3.

A deflecting wedge element 43 which is arcuate in cross-section (Figure 9) is pivotally mounted on a pin 44 which is secured within the lower end of an outer sleeve 45 formed of interconnected sleeve members. As is clearly shown in Figures 7 and 8, the sleeve 45 surrounds the lower section T4 and also surrounds the sleeve 32 as well as the lower portion of the sub 30 of the section T3. The upper end of the outer sleeve 45 is adapted to abut an external shoulder 46 formed on the sub 30 and suitable bearing material 47 may be provided on the upper end of said sleeve. The sleeve 45 is suspended from a shoulder 48 formed at the lower end of the sleeve 32, and additional bearing material 49 may be provided at this point.

For locking the outer sleeve 45 against rotation with respect to the sections and to the drill pipe to permit orientation, an orienting pin 50 and a co-acting notch 54 are provided. The pin 50 is adapted to extend inwardly from the sleeve 45 into an annular recess 51 which is formed in the exterior of the body 34 of the lower section T4. The recess 51 is defined by an upper shoulder 52 and a lower shoulder 53 and the space between the shoulders limits the movement of the outer sleeve in an axial direction with respect to the section T4. A notch or recess 54 extends upwardly from the shoulder 52, and when the orienting pin 50 is engaged within the notch, the outer sleeve is coupled to the lower section T4. At this time the deflecting element 43 is retracted and the sections T3 and T4 are extended as shown in Figure 8.

The operation of this form is substantially similar to the other form with the tool being connected between the drill pipe and the drill bit. During the lowering of the tool into the well the parts are in the position shown in Figure 8 with the spring 39 holding the sections extended. In such position, the clutch teeth 33 and 38 are disengaged, but a rotative connection between sections T3 and T4 is set up through the splines 41 and 42. The outer sleeve 45 is locked against rotation by the orienting pin and the deflecting element 43 is retracted.

After proper orientation of the deflecting element, the bit is lowered to bottom and the drill pipe weight is imposed thereon to telescope the parts. This moves the sections to the position shown in Figure 7 which releases the orienting pin 50 from the locking recess 54 and causes the deflecting element 43 to be moved radially outwardly along the inclined surface 40a of the expander 40. As is the case of the deflecting element B in the first form, a lateral pressure is imparted to the drill bit by contact of

the deflecting element 43 with the wall of the bore. At the same time that the element is expanded, the clutch teeth 33 and 38 are engaged to set up a direct drive from the drill pipe through the sections T3 and T4 to the drill bit, whereby subsequent rotation will carry out the drilling operation. It is evident that as long as the drilling operation is continued the deflecting element remains in its radially extended position, and since the orienting pin 50 has been disengaged from its recess, the sections of the tool may be rotated relative to the outer sleeve 45 and said deflecting element. Therefore, the element merely slides down the wall of the well bore and applies a lateral pressure as the drilling proceeds.

Still another form of the invention is shown in Figures 10 and 11. This modification is substantially the same as the form shown in Figures 7-9 with the exception that a different type of deflecting element is provided. As shown in Figure 10, a sleeve 45a is substituted for the sleeve 45 and a body 34a is substituted for the body 34. The body 34a which forms the main member of the lower telescoping section T4 is not provided with an expander such as 40, but rather has a substantially cylindrical surface on which an expander 140 is mounted. The expander 140 is rotatably supported on a shoulder 34b of the body 34a and said expander is formed with a trio of expander surfaces 60. Each expander surface has an arcuate deflecting wedge element 61 keyed thereon, and each deflecting element is connected through a pivoted link 62 with the lower end of sleeve 45a. As is clearly shown in Figure 11, the deflecting elements 61 are substantially arcuate in cross-section and are disposed all on one side of the tool.

For locking the expander sleeve 140 and the deflecting elements which have connection thereto against rotation on the body 34a, said sleeve is provided with an orienting pin 63 adapted to coact with a locking recess 64; the orienting pin engages said recess when the sections T3 and T4 of the tool are in extended position.

The operation of this form is exactly the same as that of the form shown in Figures 7-9. When the sections T3 and T4 are extended, the orienting pin 63 engages the recess 64 and the expander sleeve 140, together with the deflecting elements 61, are locked against rotation with respect to said sections. At this time the deflecting elements 61 are in a radially retracted position.

When the device has been lowered into the well bore and the deflecting elements properly oriented, the sections T3 and T4 are moved into fully telescoped position as shown in Figure 10. This moves the deflecting elements 61 downwardly on the inclined surfaces 60 of the expander to thereby radially expand said elements. At the same time, the orienting pin 63 is disengaged from its recess and a direct drive is set up between the sections through clutch teeth 33 and 38. Rotation of the drill pipe will rotate the sections T3 and T4 to impart rotation to the drill bit 11, and since the deflecting elements are expanded a lateral pressure is applied to the bit. Since the expander sleeve 140 has been disconnected from the body 34a of the lower section T4, it is obvious that the deflecting elements 61, the expander sleeve 140 and the supporting sleeve 45a all remain stationary as the drill pipe and its connected parts rotate to rotate the drill bit and perform the drilling operation. The main difference between the form shown in Figure 10 and that shown in Figures 7-9 is that the expander in Figure 10 does not rotate during the drilling operation, while in Figures 7-9 the expander 40 is rotatable with the drill bit.

In all forms of the invention, the deflecting element or elements is or are positively urged radially outwardly during the drilling operation, and therefore a constant lateral pressure is maintained against the drill bit. Since the deflecting element or elements may be properly oriented, it is apparent that a directional drilling operation may be accomplished.

The foregoing disclosure and description of the inven-

tion is illustrative and explanatory thereof and various changes in the size, shape and materials, as well as in the details of the illustrated construction, may be made within the scope of the appended claims without departing from the spirit of the invention.

What we claim is:

1. A deflecting tool including, an upper tubular section, a lower tubular section in telescoping relationship with respect to the upper tubular section, means interconnecting the sections for axial movement relative to each other whereby the sections may be moved to a first position in which the sections are extended and to a second position in which said sections are more fully telescoped, means for rotatively connecting the sections in all positions of the sections, spring means normally urging the sections toward said first extended position, an expander element on the lower portion of the lower section and having an external inclined surface, and a radially movable deflecting element carried by the upper section and disposed in a plane above the expanding surface of the expander when the sections are in said first position, movement of the sections to said second position effecting a movement of said deflecting element with respect to the inclined surface of the expander whereby said deflecting element is moved radially outwardly when said sections are in said second position.

2. A deflecting tool as set forth in claim 1, together with means for rotatably mounting the deflecting element on said upper section, whereby the sections may be rotated with respect to the element.

3. A deflecting tool as set forth in claim 1, together with means for rotatably mounting the deflecting element on said upper section, whereby the sections may be rotated with respect to the element, and means operable when the sections are in said first position for locking the deflecting element against rotation with respect to said sections, said last named means unlocking the deflecting element for rotation independently of the sections when said sections are in said second position.

4. A deflecting tool including, an upper section, a lower section in telescoping relationship with respect to the upper section, means interconnecting the sections for axial movement relative to each other, said sections being movable axially with respect to each other from a first extended position to a second more fully telescoped position, spring means normally urging the sections toward said first extended position, means rotatively connecting the sections in all positions of the sections, an expander having an external inclined expanding surface mounted on the lower section below the upper section, an outer sleeve rotatably suspended from the upper section, and a radially movable deflecting element suspended from the upper section and located in a plane above the expander when the sections are in extended position, said deflecting element being movable downwardly relative to the inclined expanding surface of the expander when the sections are telescoped, whereby the coaction between said expander and the element moves said element outwardly in a radial direction.

5. A deflecting tool including, an upper section, a lower section in telescoping relationship with respect to the upper section, means interconnecting the sections for axial movement relative to each other, said sections being movable axially with respect to each other from a first extended position to a second more fully telescoped position, spring means normally urging the sections toward said first extended position, means rotatively connecting the sections in all positions of the sections, an expander having an external inclined expanding surface mounted on the lower section, an outer sleeve rotatably suspended from the upper section, a radially movable deflecting element suspended from the upper section and located in a plane above the expander when the sections are in extended position, said deflecting element being movable downwardly relative to the inclined expanding surface of the

expander when the sections are telescoped, whereby the coaction between said expander and the element moves said element outwardly in a radial direction, and means operable when the sections are extended for locking the outer sleeve against rotation with respect to the sections.

6. A deflecting tool as set forth in claim 5, wherein the locking means comprises a pin within the bore of the outer sleeve and a recess formed in the external surface of the lower section.

7. A deflecting tool as set forth in claim 4, wherein the expander is formed as an integral part of the lower section.

8. A deflecting tool as set forth in claim 4, together with means for rotatably mounting the expander on the lower section, means connecting the deflecting element to the expander to prevent rotative movement while permitting longitudinal movement, and locking means operable when the sections are extended for locking the expander against rotation relative to the sections when the sections are extended relative to each other.

9. A deflecting tool including an upper section, a lower section in telescoping relationship with respect to the upper section, means interconnecting the sections for axial movement relative to each other, said sections being movable axially with respect to each other from a first extended to a second more fully telescoped position, resilient means normally urging the sections toward an extended position, means rotatably connecting the sections in all positions of said sections, 30 an expander having an external inclined expanding surface mounted on the lower section below the upper section, an outer sleeve rotatably suspended from the upper section and surrounding a portion of the lower section, an orienting projection extending inwardly from the bore 35 of the outer sleeve and adapted to engage an orienting recess formed in the surface of the lower section, said orienting projection being engaged within its co-acting recess when the sections are in said first position to latch the outer sleeve against rotation with respect to the sections, 40 said projection being disengaged from the recess when the sections are moved to said second position whereby the sections may be rotated relative to the outer sleeve, and a radially movable deflecting element suspended from the outer sleeve and located in a plane above 45 the expanding surface of the expander when the sections are in said first position, said deflecting element being movable downwardly relative to the inclined expanding surface of the expander when the sections are more fully telescoped, whereby the co-action between the expander and the element moves the element outwardly in a radial direction.

10. A deflecting tool as set forth in claim 9, together with clutch members on the upper and lower sections, which clutch members are adapted to engage each other 55 when the sections are moved to said more fully telescoped position to provide a direct rotative drive between the sections.

11. A deflecting tool as set forth in claim 9, wherein the expander is rotatably mounted upon the lower section.

12. A deflecting tool adapted to be lowered in a well bore by the drilling string and being positioned adjacent the drill bit, comprising an upper section, a lower section having a telescoping connection with the upper section, said sections being movable axially with respect to each other from an extended position to a retracted position, resilient means normally urging the sections toward an extended position, means rotatably connecting the sections in all positions of the sections, an expander having an external surface mounted on the lower section below the upper section, a radially movable deflecting element arranged to cooperate with said surface when said sections are moved from their extended position to a retracted position and thereby gradually move radially outwardly with respect to the bit to engage the bore and impart lateral thrust to the bit, said element being po-

sitioned within the gauge of said bit and in a plane above the expander when the sections are in extended position, and said element being positioned outside of the gauge of the bit when said sections are in a retracted position.

13. A deflecting tool, as set forth in claim 12, together with latching means between the deflecting element and the lower section, said latching means comprising a recess and a projection engageable within said recess, said elements which comprise said latching means being disposed one on the deflecting element and the other on the lower section, the position of said projection and recess being such that the projection is engaged with the recess when the upper and lower sections are in an

extended position with respect to each other to thereby lock the deflecting element against rotation relative to said lower section and said projection is disengaged from said recess when the sections are in retracted position, whereby the inner section may be rotated independently of said deflecting element.
